DESIGN FOR A CANDLE BASE

Alfons Bach, Stamford, Conn., assignor to Syracuse Ornamental Co. Inc., Syracuse, N. Y., a corporation of New York

Application April 12, 1946, Serial No. 128,513

Term of patent 7 years

(Cl. D48—2)

To all whom it may concern:

Be it known that I, Alfons Bach, a citizen of the United States, residing in Stamford, in the county of Fairfield and State of Connecticut, have invented a new, original, and ornamental Design for a Candle Base, of which the following is a specification, reference being had to the accompanying drawing, forming a part thereof, wherein:

Fig. 1 is a top view of a candle base showing my new design; and

Fig. 2 is a perspective view taken from beneath and to one side of the said candle base.

I claim:

The ornamental design for a candle base, substantially as shown.

ALFONS BACH.
